FIGURE 4 is a side elevation thereof taken from the right and illustrating the oven in open position, the opposite side being a mirror image of this disclosed side; and

The rear of the portable oven or the like is substantially plain, except for the overlap of the top over the bottom portion.

I claim:

The ornamental design for a portable oven or the like, substantially as shown and described.
